United States Patent Office.

ROBERT DUNN, OF BROOKLYN, N. Y., ASSIGNOR TO THE WATERBURY CLOCK COMPANY, OF WATERBURY, CONNECTICUT.

Design No. 4,421, dated October 18, 1870.

DESIGN FOR A CLOCK-CASE.

The Schedule referred to in these Letters Patent and making part of the same.

To all whom it may concern:

Be it known that I, ROBERT DUNN, of Brooklyn, in the county of Kings and State of New York, have invented a new and original Design for a Clock-Case; and I do hereby declare that the following is a full, clear, and exact description thereof, which will enable others skilled in the art to make and use the same.

The nature of my design is fully represented in the annexed photograph, to which reference is made.

I claim as my invention—

The design for a clock-case, as shown.

ROBERT DUNN.
